MULTIPLE FUSE PLUG

Filed May 27, 1948

UNITED STATES PATENT OFFICE

2,492,301

MULTIPLE FUSE PLUG

William C. Linton, Washington, D. C.

Application May 27, 1948, Serial No. 29,571

2 Claims. (Cl. 200—121)

1

The present invention relates to fuse units of the multiple plug fuse type and the primary object of the invention is to provide a suitable enclosure for multiple plug fuses which shall be sufficiently tight to prevent lint and dust collecting around the fusible links therein and becoming ignited when a fusible link is blown and yet each fusible link will be in place for performing successively when short-circuits occur.

Other objects will be in part obvious and in part pointed out hereinafter.

In the accompanying drawings:

Fig. 1 is a side elevation of the fuse unit embodying the invention.

Fig. 2 is a vertical transverse sectional view.

Fig. 3 is a vertical transverse sectional view taken substantially at right angles to that of Fig. 2.

Fig. 4 is a horizontal sectional view taken on the line 4—4 of Fig. 2 in the direction of the arrow points.

Fig. 5 is a plan view of the cover plate.

Fig. 6 is a fragmentary enlarged plan view of the casing.

Fig. 7 is a perspective view of one of the fuse links.

Fig. 8 is a plan view of the floating contact, and

Fig. 9 is a section of the latter taken on the line 9—9 of Fig. 8 in the direction of the arrow points.

This multiple plug-type fuse unit comprises a casing 1 preferably formed from porcelain having external threads for receiving a conventional screw contact shell 2. A flat headed contact rivet 4 extends through the casing 1 and is provided with a split extremity 3.

The casing 1 is provided with a centrally located chamber 5 and an opening 6 through which extends rivet 4. Radially extending from and communicating with the chamber 5 are a plurality of vertically extending compartments 7, preferably eight in number, and each capable of receiving a fusible link 8. Each compartment 7 is of sufficient area, as best shown in Fig. 4 of the drawings, as to permit any molten metal given off by the rupture of the weakened portion of the fuse link therein to remain or settle therein and the separating walls between each compartment prevent the spattering of this molten metal into an adjacent compartment as would render the fuse link therein inoperative. The upper end of the casing 1 is enlarged to provide an annular flange 9. Formed within the upper face of this casing is an annular groove or chan-

2

nel-way 10 establishing a flat surface 11 upon which rests the brass contact ring 12 and a flat annular surface 13 which latter separates the fuse link compartments 7 from the channel-way 10. Shallow recesses 14 are also formed in the upper face of the casing to establish the flat surface 15 over each of which extends the upper bent over section 16 of a fusible link 8. Also formed diametrically opposite within the casing 1 are the vertically extending slots 17 through each of which extend a leg 18 bent downwardly from the brass contact ring 12 and the outer extremities of these legs 18 are connected to the screw contact shell 2 by means of the solder connections 19.

A cover plate 20 preferably moulded from Bakelite extends over the upper end of the casing 1 and has an outer flange 21 which latter is capable of riding within the annular groove 22 of the casing and is provided with a centrally located boss extending within the chamber 5. A washer 23 is placed upon the central portion of the cover plate 20 and the split ends 3 of the contact rivet extend thereover for retaining the cover plate upon the casing and yet permit the free rotation thereof. This plate 20 is also provided with a depending annular flange 24 projecting within the channel-way 10 of the casing.

A housing 25 is formed with the cover plate 20 having a compartment therein in which freely floats a contact plate 26. This contact plate is stamped from one piece of brass having one arm 27 capable of riding upon the contact ring 12 and its opposite arm 28 adapted to contact with each upper end 16 of the fusible links. A coil spring 29 is also provided for normally retaining the arms 27 and 28 in contact with the ring and fusible links.

A depending leg 30 is also formed with the contact plate 26 and extends within the annular channel-way 10 of the casing so that when contacting the cam-shaped lugs 31 this contact plate 26 will be moved upwardly out of contact with the ring 12 and fusible links.

A pair of spaced lugs 32 are formed with the upper face of the cover plate and have a snap-on connection with the lamp housing 33. Arranged within the lamp housing is a neon indicating lamp 34 and leak resistor 35. One lead wire 36 of the lamp extends beneath the washer so as to have a connection with the contact rivet 2 whereas another lead wire 37 connects the lamp and resistor 35 in series with the coil spring 29.

Formed within the upper face of the housing 25

is a recess 38 and extending diametrically therethrough is a vertical wall or partition 41 for dividing the recess into two separate compartments. An opening 42 leads within one compartment and through which extends one end of the coil spring 29. The other compartment has a post or knob 43 projecting upwardly therein around which extends a loop formed with the outer extremity of the lead wire 37. This lead wire 37 extends through a slot 44 as it enters the recess 38. From this it is apparent that the coil spring 29 is separated from the lead wire 37 and by placing within the recess 38 any suitable resistance composition or that disclosed in my former Patent No. 2,206,780, dated July 2, 1940, a leak resisting connection 35 will be established therebetween.

Within the chamber 5 and about the fusible links within the compartments 7 is placed an arc quenching material 39 such as granular sulphate or carbonate or a mixture of both. Any suitable binder may be employed for retaining the granular arc quenching materials in place about the fusible link. Solder 40 connects the fusible links with the rivet 2 and also prevents the latter from rotating within the casing 1.

By grasping the lamp housing 33 and turning the same in a clock-wise direction the contact plate 26 will be caused to move therewith until the curved forward end of the leg 38 rides one of the lugs 31 whereupon the contact plate 26 will be moved upwardly and out of contact with the ring 12 and a fusible link. Upon further rotation the leg 30 will pass over the lug 31 and again drop within the channel-way 10 so as to effect a snap contact with the ring 12 and the next succeeding fusible link. Each lug 31 is provided with an inclined surface so that the curved forward end of the leg 30 may ride thereupon, but the outer extremity of the leg 30 will prevent the cover plate from turning in an anti-clockwise direction by contacting the straight wall of a lug 31 opposite to that where the inclined surface is formed.

As the lamp is connected in series with the contact terminals 2 and 3 but in parallel with the fusible links it will glow only when a fusible link 45 is blown due to a short circuit or overloading.

I claim:

1. A multiple fuse plug comprising in combination a casing, a rivet contact centrally located within said casing, a screw shell contact surrounding said casing and spaced from said rivet contact, a contact ring mounted within said casing and connected to said screw shell contact, fuse links each having one end connected to said rivet contact, said casing having an annular channel-way formed therein and arranged between said contact ring and the opposite ends of said fuse links, cam shaped projections formed

with said casing and extending within said channel-way thereof, a cover plate rotatably mounted upon said casing, a flange carried by said cover plate and projecting within said channel-way for separating said contact ring from said fuse links, a contact plate carried by said cover plate, means for normally retaining said contact plate in contact with said contact ring and one of the ends of said fuse links arranged adjacent said channel-way within the said casing and a depending leg formed with said contact plate whereby upon the rotation of said cover plate said depending leg will be caused to ride upon said cam shaped projection for moving said contact plate out of contact with said contact ring and one of the ends of said fuse links against the action of said contact retaining means.

2. A multiple enclosed plug fuse comprising in combination a moulded casing, an enlarged annular flange formed with the upper end of said casing, said casing having an explosion chamber formed therein opening through said annular flange formed with the upper end thereof, said casing having an annular channel-way formed in 20 the upper face thereof between said explosion chamber and said flange, lugs formed with said casing and positioned equidistance apart within the channel-way thereof, a contact rivet, a screw shell contact, a contact ring mounted upon said 25 flange and connected to screw shell contact, fuse links arranged within the explosive chamber of said casing each having one end connected to said rivet contact, a rotatable cover plate, a contact member carried by said cover plate, means 30 whereby upon the rotation of said cover plate said lugs will cause said contact member to be moved into and out of contact with said contact ring and the free ends of said fuse links, a flange 35 formed with said cover plate and depending 40 within said channel-way
